LOCKING DEVICE FOR WARDROBE TRUNKS

John Luft, Oshkosh, Wis., assignor to Oshkosh
Trunks and Luggage, Oshkosh, Wis., a corpora-
tion of Wisconsin

Application March 3, 1947, Serial No. 731,917

5 Claims. (Cl. 70—72)

1

This invention relates generally to a wardrobe trunk having at least two compartments each of which is accessible through its own door. More particularly my invention is concerned with a simple and effective locking mechanism which is adapted to lock or unlock, in one operation, the doors of the several compartments. In accomplishing this objective, I utilize a linkage system comprising locking parts which are sturdy and simple, and also compact so as to occupy the minimum of space. More particularly, the locking mechanism operates to impart a final closing, and also an initial opening, movement to one of the doors, depending upon whether it is being operated to locking or unlocking position.

As a suggestive embodiment of my invention, I have shown in the accompanying drawings, in

Fig. 1, a perspective view, partly broken away to exhibit the principal parts of the locking mechanism which is carried within the wardrobe compartment of the trunk;

Fig. 2, a similar view in which the locking mechanism is shown as retracted to an unlocking position;

Fig. 3, a horizontal section through the trunk, taken on line 3—3 of Fig. 1;

Fig. 4, an enlarged fragmentary detail in vertical section showing the operating mechanism in its locked position; and

Figs. 5, 6, and 7, details in section taken, respectively, on lines 5—5, 6—6, and 7—7, of Fig. 4.

The trunk here shown by way of illustration is of the partitioned type in that it comprises one section which may be termed a wardrobe compartment A separated by a wall 10 from another section which may be termed a chiffonier compartment B. The walls enclosing the chiffonier compartment include also a door 11 which is extended around in line with one corner of the trunk in the form of a flange 12 which is hingedly connected as at 13 to the proximate wall of the trunk. Access to the wardrobe section A is provided by a door 15 which extends around in line with another corner of the trunk to provide a flange 16 having a hinge connection at 17 with the proximate wall of the trunk. The opposite free edge of this door is also angled to provide a second flange 18, parallel with the first flange 16, adapted to lie adjacent the proximate trunk wall 19 to which it may be locked in the manner presently to be described.

The chiffonier door 11 carries near its free edge upper and lower keepers 20 each having a base 21 which may be secured at spaced points

to the door 11. A protecting strip 22 which is carried by the door 11 along its free edge covers the keeper bases to conceal the same from view exteriorly of the trunk.

5 The trunk wall 19 proximate to the swinging free edge of the door 11 is provided with a pair of slots 26 at points opposite the keepers 20 which are accordingly free to be advanced therethrough so as to present closed slots 27 formed therein 10 wholly within the wardrobe compartment. The positions of the keepers, when the door 11 is closed, are proximate to the partition wall 10.

Rotatably mounted upon the exterior of the trunk wall 19 is a hasp H having a locking arm 15 31 in hinged connection at 32 with a hub 33 from which is axially extended a stud 34 of non-round cross section which passes through the trunk wall 19 to project within the wardrobe compartment. A bearing plate 36 may be interposed between the hasp hub 33 and the outer face of the trunk wall 19, and upon its inner face, opposite thereto, I affix a second bearing plate 37 which along its bottom edge is formed into an upwardly facing channel 38. Fitted non-rotatably on to

20 the stud is a partial gear 40 whose teeth 41 are in mesh with those of a rack bar 42 which extends along the inner face of the trunk wall 19 in a generally horizontal direction. The bar end 25 proximate to the gear 40 is slidingly supported

between the hasp hub 33 and the outer face of the trunk wall 19, and upon its inner face, opposite thereto, I affix a second bearing plate 37 which along its bottom edge is formed into an upwardly facing channel 38. Fitted non-rotatably on to

25 the stud is a partial gear 40 whose teeth 41 are in mesh with those of a rack bar 42 which extends along the inner face of the trunk wall 19 in a generally horizontal direction. The bar end 20 proximate to the gear 40 is slidingly supported

30 in the channel 38, whereas the opposite bar end 35 is fitted slidingly through a strap-guide 43 which is carried by the wall 19 at a point relatively close to the upper keeper 20. When the hasp H is rotated about its axis, motion is transmitted

35 from its spindle 34 to the partial gear 40 whereby to reciprocate the rack bar 42. In one position (Figs. 1 and 4) the bar is advanced toward the partition wall 10 so as to enter through the slot 27 of the keeper 20, thereby locking the door 11 in a closed position to safeguard the chiffonier compartment therewithin. In its op-

30 posite position (Fig. 2), the rack bar is retracted a distance sufficient to disengage from the keeper 20 whereby to free the door 11 for opening movement.

40

45 A crank arm 45 is extended radially from the spindle 34 to rotate therewith. Near the end of the crank arm is a pivotal connection 46 with a link 47 which is extended vertically along the 50 wall 19 close to its opening into the wardrobe compartment adjacent the free edge of the door flange 18. This link near its lower end is pivotally connected at 48 with a cam-latch arm 49 pivoted to the trunk wall 19 at 50, and having 55 its free end extended beyond the proximate edge

of said wall to lap past the door flange 18. The position of this latch-cam arm is desirably medially of the trunk top and bottom (see Figs. 1 and 2). The free end of the latch-cam arm is provided with a relatively long depending arcuate cam 52 defining one edge of a deep slot 53 whose opposite edge is defined by a slightly shorter depending arcuate finger 54 adapted to enter the slot 55 of the keeper bar 56 which is anchored to the flange 18 of the door 15. When in the down position shown in Figs. 1 and 4, the latch-cam arm secures the wardrobe compartment door 15 in closed position.

Also in pivotal connection, at 48, with the latch-cam arm 49 is the upper end of the second link 60 which depends to a point relatively close to the trunk bottom to establish at its lower end pivotal connection at 61 with a locking arm 62 which is pivoted to the trunk wall as at 63. At the point of connection between the link 60 and the locking arm 62 the latter may be provided with an endwise slot 61a wherein the pivot 61 is free to shift as required by a slight swinging movement of the link 60 through its pivotal connection, at 64, with a crank arm 65 which is extended non-rotatably from a stud 66 that is mounted for movement in an anchor plate 67 that is carried by the trunk wall 19. The bottom edge of this anchor plate is formed into an upwardly facing channel 70 for slidably supporting one end of a rack bar 71 which is extended along the inner face of the trunk wall 19 in a generally horizontal direction. Mounted on the stud 66 for rotation therewith is a partial gear 72 whose teeth 73 are in mesh with those of the rack bar 71 to impart longitudinal movement thereto. The end of the rack bar 71 which is remote from the gear 72 may be fitted slidably through a strap-guide 75 which is carried by the wall 19 at a point relatively close to the lower keeper 28. By the linkage of parts described up to this point, I provide for concurrent movement of the rack bars 71 and 42, both in the same direction and desirably for the same distance, whereby to engage and disengage in unison the two keepers 28.

The locking arm 62 is provided with a downwardly facing slot 80 bounded to the outside by the convex face 81 of a depending finger 82 which is adapted to enter the slot 83 of a second keeper bar 84 which at an opposite point is anchored to the flange 18 of the door 15. In the position of Figs. 1 and 4 wherein the cam-latch arm 49 is engaged with the keeper bar 56 the locking arm 62 near the trunk bottom is also engaged with its keeper bar 84 so that the trunk door 15 is secured in closed position at two spaced points. This position is reached only when the hasp H, serving as a handle, has been swung down horizontally (see Fig. 1) to a point opposite a socket keeper 87 anchored to the door flange 18 exteriorly thereof, for reception of oppositely extended latch bolts 88 which are projected radially from a key operated lock cylinder 89 that is carried by the hasp adjacent its free end. The hasp accordingly provides a further means of securement for the wardrobe door at a point near its top. Its locking engagement follows after that of the cam-latch arm 49 whose operation to locking position also precedes that of the locking arm 71. Conversely, the hasp H is the first of the three locking means to become disengaged from the trunk door 15, the locking arm 71 is second, and the cam-latch arm 42 is the last.

It will be noted that the finger 54 of the cam-

latch arm 49 is concavely bowed where it faces the slot 53 whereas the finger 82 of the locking arm 62 is convexly bowed at the same point; also that the long arcuate face of the cam 52 is curved (symmetrically or otherwise) about a radius much longer than one reaching to the axis of the pivotal connection 50 between the cam-latch arm and the trunk wall 19. When swung upwardly from the position of Fig. 4 to that of Fig. 2, the arcuate face of this cam moves outwardly an increasing distance from the pivot point 50, and in so doing exerts a camming thrust upon its associated keeper bar 56. The effect of this is to open the door 15 a slight distance before it is fully released. With the door so ajarred initially, following release of the hasp H and the locking arm 62, a further and complete opening movement of the door is facilitated. When in its topmost position, the cam 52 at its lower end stands opposite the keeper bar 56 so as to prevent complete closing of the door by engaging with the keeper plate, unless the hasp be then rotated about the center of its hub to operate the linkage system and lower the cam-latch arm to its locking position. In this movement the convex face 81 of the finger 82 of the locking arm will act as a cam to force the door 15 near its bottom to a tightly closed position. It will thus be noted that in the operation of unlocking the door the cam-latch arm 49 exerts a thrust force for imparting an initial opening movement to the door, and in the operation of locking the door the locking arm 62 exerts a tension force for imparting a final closing movement to the door.

For clarity in illustration I have omitted any showing of a conventional covering strip whereby to prevent contact between the linkage system and garments contained within the wardrobe compartment. My invention relates primarily to a key controlled locking mechanism which operates concurrently to secure or free two doors, otherwise completely independent, opening into separate compartments of the same trunk, and which provides for one door sequentially-operating multiple locking means acting both to initiate opening movement and complete final closing movement of the door.

I claim:

1. In a wardrobe trunk, a locking device adapted for locking two separate doors, comprising spaced spindles, spaced slideable bolts each provided with rack teeth, a gear element mounted on each spindle and each meshing with the rack teeth of one of the bolts for reciprocating the same, a crank arm mounted on each spindle, spaced pivotally mounted latch arms spaced from the bolts, and a linkage arranged substantially at right angles to the bolts and connecting the crank arms of the spindles with each other and with the pivoted latch arms for actuating said latch arms simultaneously with the bolts.

2. In a wardrobe trunk, a locking device adapted for locking two separate doors, comprising spaced spindles, spaced slideable bolts provided with rack teeth, a gear element mounted on each spindle and each meshing with the rack teeth of one of the bolts for reciprocating the same, a crank arm mounted on each spindle, spaced pivotally mounted latch arms spaced from the bolts, a linkage arranged substantially at right angles to the bolts and connecting the crank arms of the spindles with each other and with the pivoted latch arms for actuating said latch arms simultaneously with the bolts, and a key controlled lock having a hasp connected with

one of the spindles for rotating the same to actuate the bolts and the latch arms simultaneously.

3. In a wardrobe trunk, a locking device adapted for locking two separate doors comprising spaced spindles, substantially parallel spaced slideable bolts provided with rack teeth, gear elements fixed to the spindles and meshing with the rack teeth for reciprocating the bolts, crank elements also fixed to the spindles, longitudinally aligned links arranged substantially at right angles to the bolts and pivotally interconnected at their adjacent ends, one of the links being pivoted at its other end to one of the crank elements and the other link being pivoted adjacent its other end to the other crank element and extended beyond the same to provide a projecting portion, and spaced pivoted latch arms, one of the latch arms being connected to the pivotally interconnected ends of the links and the other latch arm being pivotally connected to said projecting portion of said other link.

4. In a wardrobe trunk, a locking device adapted for locking two separate doors comprising spaced spindles, substantially parallel spaced slideable bolts provided with rack teeth, gear elements fixed to the spindles and meshing with the rack teeth for reciprocating the bolts, crank elements also fixed to the spindles, longitudinally aligned links arranged substantially at right angles to the bolts and pivotally interconnected at their adjacent ends, one of the links being pivoted at its other end to one of the crank elements and the other link being pivoted adjacent its other end to the other crank element and extended beyond the same to provide a projecting portion, spaced pivoted latch arms, one of the latch arms being connected to the pivotally interconnected ends of the links and the other latch arm being pivotally interconnected to said projecting portion of said other link, and a key controlled

lock having a hasp connected with one of said spindles for rotating the same to operate the sliding bolts and the latch arms simultaneously.

5. In a wardrobe trunk, a locking device comprising spaced spindles, bearing means for mounting the spindles on a trunk, said bearing means being provided with channel guides, substantially parallel slideable bolts provided with rack teeth and arranged in and guided by said channel guides, gear elements fixed to the spindles and meshing with the teeth of the bolts for reciprocating the latter, crank elements also fixed to the spindles, a linkage arranged substantially at right angles to the bolts and connecting the crank elements, and a key controlled lock having a hasp connected with one of the spindles for rotating the latter for simultaneously reciprocating the bolts in the same direction.
